UNITED STATES PATENT OFFICE.

DANIEL KOPS, OF NEW YORK, N. Y.

APPAREL-CORSET.

SPECIFICATION forming part of Letters Patent No. 767,415, dated August 16, 1904.

Application filed November 3, 1903. Serial No. 179,669. (No model.)

To all whom it may concern:

Be it known that I, DANIEL KOPS, a citizen of the United States, residing in the borough of Manhattan, in the city, county, and State 5 of New York, have invented an Improvement in Apparel-Corsets, of which the following is a specification.

My invention relates to an apparel-corset having the function of modifying or building 10 up the figure at the hips, the object being to provide a corset fulfilling such requirements for both slim and stout figures in which correction is required in the form.

My improvement is especially adapted to a 15 corset long in front, short at the back, and cut up over the hips—that is, short on the hips.

In carrying out my invention I provide the corset with fabric flaps of peculiar form, each 20 having a curved convex union or connection to the body of the corset at about the waist-line. The flaps come at the respective sides of the corset over the hips, and at their lower ends they are adapted for connection with 25 hose-supporters, the action of which is to draw down the flaps and with large hips to press down and spread out the flesh to give a more acceptable contour to the figure of the wearer and round off or merge with the waist 30 contour, while where the figure is too slim the same can be filled out or padded beneath the flaps, which will act to keep the additional parts in place, especially when drawn and held down by the hose-supporters. I prefer 35 to double-bone the under-arm portions of the corset down to the waist-line, and the corset is made with other special features, hereinabove more particularly set forth.

In the drawings, Figure 1 is a side elevation of one side of, or, in other words, one-half of, a corset according to my invention. Fig. 2 is a vertical central or under-arm section at $x x$ of Fig. 1. Fig. 3 is a horizontal section at $x' x'$ of Fig. 1. Fig. 4 is a horizontal section at $y y$ of Fig. 1. Fig. 5 is a horizontal section at $y' y'$ of Fig. 1. Fig. 6 is a horizontal section at $z z$ of Fig. 1, and Fig. 7 is a vertical central section of a modi-

fication. Figs. 3, 4, 5, and 6 are of larger size for clearness.

a represents the corset-body; b , the front steels; c , the back steels, between which are the lacing-eyelets c' . The corset-body is made up in any desired manner, so far as the strips from which the same is composed are concerned, and the boning may be arranged in any preferred manner. The corset shown is long in front, short at the back, and cut up over the hips—that is to say, the part over the hips is short on the hips in contradistinction to being long, as usual.

In the preferred form of my invention d represents the flap, which forms the essential portion. This flap is of elongated form vertically, and is preferably made with a reinforced 65 edge. The edge nearest the front steels is approximately straight and receding from its point of connection with the corset, so that this edge when taken in connection with the lower front edge of the corset constitutes a 70 convex configuration at the upper portion of the limb. The rearward edge of the flap preferably has two members, the upper part following the line of the bones to the lower edge of the corset, the edge then extending 75 forward to meet the opposite edge at a point distant from the curved connection of the flap to the corset and at a place adapted for connection thereto of the hose-supporters. This flap has a convex upper edge, and there is an 80 upper fabric section d' , having a convex lower edge, which is joined to the flap d by a line of sewing 2. This fabric section d' with the convex lower edge spans the hip portion of the corset from the point 7 to the point 8 at 85 the lower edge, and the same preferably extends upward over the under-arm portion of the corset to the top edge of the corset and is fastened to the corset-body by lines of sewing 3, which lines are three in number. From 90 the section Fig. 2 it will be apparent that the line of sewing 2, which connects the upper edge of the flap d to the lower edge of the fabric section d' , does not connect said parts to the corset-body, but only connects them together. Consequently the wearer of this cor-

set could, if desired, disconnect the parts at this line of sewing 2 without affecting the connection of the fabric section d' to the body of the corset. The fabric section d' is of substantially elongated triangular shape.

c represents the side steels of the corset—that is to say, the under-arm steels that extend between the upper and lower edges of the corset and which are preferably secured in the bone-pocket strips superimposed upon the under surface of the corset-body.

f represents bones superimposed upon the under-arm portion of the corset and against the outer surface of the corset - body *a* in 15 pockets formed by vertical lines of sewing 6. The bones *f* extend from the upper edge of the corset only down to the waist-line and terminate in their pockets at the convex line of sewing 3, and I prefer in forming the 20 pockets for the bones *f* to employ an underlying strip *g* of fabric superimposed upon the under side of the strip *d'*. The bones *f* lie over and outside of the bones *e* for the length of the bones *f*.

25 In the manufacture of the corset just described the following order is preferably employed: The corset-body is formed complete of the several pieces with the front steels, the back steels and eyelets, the bones and bone-pockets, including the side or under-arm steels *e*. The flap *d* and the fabric section *d'* are then after being cut to shape connected by the line of sewing 2. The strip *g* is then sewed to the fabric section *d'* by the lines of 30 sewing 6 to form the pockets for the bones *f*. The connected flap *d* and fabric section *d'* are then laid upon the side of the corset on the under-arm portion, as illustrated in Fig. 1, and connected, the rear line of sewing 35 3 being continuous from the top of the corset to the point 7 and the second line 3 being continuous from the point 7 to the edge of the side steels *e*. The corset is then turned, so that the continuation of this curved line 40 3 only connects the fabric section *d'* and the strip *g* for the width of the side steels *e*. The corset is then turned back and the sewing continued from the opposite side of the steels *e* to the edge of the bones *e'*. The corset is 45 50 then turned, so that the sewing simply is in the fabric section *d'* until the opposite edge of the bones *e'* is reached. The balance of this curved line of sewing is then through the body of the corset to the point 8. The 55 forward and downwardly-extending line of sewing 3 from the upper edge of the corset on the right-hand side of the fabric section *d'* extends from the upper edge to the edge of the bones *e'*, then simply through the material of the fabric section *d'* to the opposite edge of the bones *e'*, and then joins the curved line of sewing previously described. There 60 is also a line of sewing 9 from the lower edge of the corset through the lower end of the

fabric section d' up to the line of sewing 2, 55 that connects the flap d with the fabric section d' . Consequently at the base of the bones f there is an opening between the fabric section d' and the surface of the corset-body a , and there is also an opening between the fabric section d' and the corset-body over the bones e' . This is necessarily so, as it would be impossible to sew through the bones or to sew through the bone-pockets, closing the same off, and it would be an unsightly construction to first connect the fabric section d' with the corset-body by the lines of sewing 3. I have placed on the drawings the numerals 4 45 5, so as to indicate the lines where the sewing is only in the fabric section d' 80 over the bones e' . The bones f , superimposed upon the side steels or bones e , coact, so as to increase the stiffness and rigidity of the corset at the under-arm portions and in a measure overcome any buckling effect that might 85 be produced by the hose-supporters drawing upon the flap d . At the same time the portions of the side steels e below the lower ends of the bones f possess the necessary flexibility for yielding at the union of the waist-line and 90 upper portions of the hips in giving contour to the figure.

The flap d may, as shown in Figs. 1, 2, and 6, be made with an under fabric section h , forming between the two a pocket to receive 95 suitable filling material to build out the figure where this is required. In fact, I prefer to employ a pocket-flap.

I do not herein limit myself to employing two parts—the flap *d* and fabric *d'*—as one piece of the outline of the two parts may be employed in lieu thereof and connected to the corset by similar lines 3 of sewing, the one piece having otherwise all the characteristics and functions of the two except that of separation, as stated. Fig. 7 is a section illustrating this form of my invention. 100 105

I claim as my invention—

1. In a corset, the combination with the fabric body, of a fabric section secured to the side of the corset at the under-arm portion and at a line above the lower edge of the corset, and having a prolongation thereof constituting a flap free of the said fabric body of the corset from the said line of attachment to the said body, the free end of said prolongation being adapted for connection with hose-supporters. 110 115

2. In a corset, the combination with the fabric body, of a fabric section secured to the side of the corset at the under-arm portion and at a line above the lower edge of the corset, and having a prolongation thereof constituting a flap free of the said fabric body of the corset from the said line of attachment to the said body, and a fabric section agreeing substantially in form with and secured to the under surface of said prolongation and form- 120 125

ing a pocket, the free end of said prolongation being adapted for connection with hose-supporters.

3. In a corset, the combination with the fabric body, of a fabric section secured to the side of the corset at the under-arm portion and having a prolongation thereof constituting a flap free of the said fabric body from a line of sewing to the fabric body, the free end of said prolongation being adapted for connection with hose-supporters, the lower line of sewing of said fabric section to the corset-body conforming generally to the hip contour, and bones at the under-arm portion and superimposed upon the side steels of the corset in pockets formed independent of the side-steel pockets and with said fabric section.

4. In a corset, the combination with the fabric body, of a fabric section secured to the side of the corset at the under-arm portion and having a prolongation thereof constituting a flap free of the said fabric body from a line of sewing to the fabric body, and a fabric section agreeing substantially in form with and secured to the under surface of said prolongation and forming a pocket, the free end of said prolongation being adapted for connection with hose-supporters, the lower line of sewing of said fabric section to the corset-body conforming generally to the hip contour, and bones at the under-arm portion and superimposed upon the side steels of the corset in pockets formed independent of the side-steel pockets and with said fabric section.

5. In a corset, the combination with a fabric section secured to the side of the corset at the under-arm portion and at a line above the lower edge of the corset, of a part forming a flap secured to the lower edge of said section by an independent line of sewing, and free from said line of attachment to the corset-body outward, the free end of said flap being adapted for connection with hose-supporters.

45 6. In a corset, a fabric section secured to the surface of the corset at the under-arm portion and at a line above the lower edge of the corset and having a curved lower edge conforming generally to the hip contour, a flap having a curved upper edge secured only to the curved lower edge of said fabric section and adapted at its free end for connection to hose-supporters.

7. In a corset, a fabric section secured to the surface of the corset at the under-arm portion, having a curved lower edge conforming generally to the hip contour, said fabric section extending to the upper edge of the corset with converging edges at which it is secured to the corset-body, bones at the under-arm portion and superimposed upon the side steels of the corset in pockets formed with said fabric section, a flap having a curved upper edge and secured only to the curved under edge of the aforesaid strip by a line of sew-

ing, said flap having a substantially straight forward edge and a bent back edge and adapted at its lower end for connection with hose-supporters.

8. The combination in a corset with the corset-body, the under-arm side steels *e* and the adjacent forward bones or steels *e'*, of a fabric section of elongated triangular form having a curved lower edge, a flap having a curved upper edge secured to the curved edge of the fabric section by a line of sewing 2, the fabric section superimposed upon the side of the under-arm portion of the corset over the upper part of the steels *e* and secured to the corset-body by three lines of stitches 3 except at the points 4, 4 and 5, 5.

9. The combination in a corset with a corset-body, the under-arm side steels *e* and the adjacent forward bones or steels *e'*, of a fabric section of elongated triangular form having a curved lower edge, a flap having a curved upper edge secured to the curved edge of the fabric section by a line of sewing 2, the fabric section superimposed upon the side of the under-arm portion of the corset over the upper part of the steels *e* and secured to the corset-body by three lines of stitches 3, except at the points 4, 4 and 5, 5, and a strip of fabric *g* connected to the fabric section *d'* alone by lines of sewing 6 forming bone-pockets, and bones *f'* in said pockets superimposed upon the side steels *e*.

10. The combination with the corset-body having front steels, back steels and lacing-eyelets between the back steels, of a side fabric section *d'* of substantially elongated triangular form having a curved lower edge and the other edges converging and secured to the corset-body by lines of sewing 3, of a flap *d* of fabric connected to the curved lower edge of the fabric section *d'* only by a line of sewing 2 and removable therefrom by cutting the line of sewing 2 without removing the fabric section *d'* from the corset-body, said flap having a reinforced edge and a forward edge that is substantially straight, and a back edge of two parts, one following the bones of the corset and the other converging to the lower end of the straight front line and adapted at its lower free edge for connection with hose-supporters.

11. In a corset, the combination with a corset-body, of a flap of appreciable width connected to the fabric body at a point above the bottom edge and adjacent to the waist-line, and extending appreciably below the lower edge of the corset over the hips and adapted at its free end for connection to hose-supporters.

12. In a corset, the combination with a corset-body, of a flap of appreciable width having a curved upper edge generally conforming to the hip contour and connected to the fabric body at a point above the bottom edge adjacent to the waist-line and extending below the lower edge of the corset over the hips.

hips and adapted at its free and lower end for connection to hose-supporters.

13. In a corset the combination with a corset-body, of a flap having a curved upper edge generally conforming to the hip contour and connected to the fabric body at a point above the bottom edge or at about the waist-line, and a fabric section agreeing substantially in form with, underlying and secured to the flap

and forming a pocket, and adapted at its free end for connection to hose-supporters.

Signed by me this 30th day of October, 1903.

DANIEL KOPS.
